UNITED STATES PATENT OFFICE.

HARRY E. DE VAUGHN, OF MORGANTOWN, WEST VIRGINIA, ASSIGNOR TO WALTER A. JONES, OF MORGANTOWN, WEST VIRGINIA.

WINDOW-GLASS BLOWING OR DRAWING MACHINE.

1,187,277.

Specification of Letters Patent. Patented June 13, 1916.

Application filed November 9, 1914. Serial No. 871,077.

To all whom it may concern:

Be it known that I, HARRY E. DE VAUGHN, a citizen of the United States, residing at Morgantown, in the county of Monongalia and State of West Virginia, have invented new and useful Improvements in Window-Glass Blowing or Drawing Machines, of which the following is a specification.

This invention is an improved combination telescope cup and air relief valve for the bait stem of a window glass blowing or drawing machine.

One of the objects of the invention is to provide means for obtaining a firm and practical connection between the bait and the air supply of a glass drawing machine.

A further object is to provide means for obtaining a variable relief of the air pressure.

The invention will be hereinafter fully set forth and particularly pointed out in the claims.

In the accompanying drawing: Figure 1 is a side view of a portion of a glass drawing machine with my invention applied thereto. Fig. 2 is a longitudinal sectional view of my improved telescope cup and air relief valve. Fig. 3 is a transverse sectional view thereof. Fig. 4 is a detail perspective view illustrating the cam slot.

Referring to the drawing, the cup 10 is formed of a hollow cylindrical body, having a cup 11 removably secured to one end thereof, and a reduced threaded portion 12 at the other end, said threaded portion terminating in a shoulder 13. The body 10 is also threaded at 14 below the shoulder 13. Said body is also provided with vent openings 15 and 16, the opening 15 being smaller in volume than that at 16. The exterior surface of the body 10 is provided with a recess 17 having depressions 18 and 19, as clearly illustrated in Fig. 4.

Rotatably mounted upon the body 10 is an eccentric ring or valve 20, provided with a threaded opening to engage the correspondingly threaded portion 21 of a handle 22, said handle having a projection 23 engaging the recess 17 and depressions 18 and 19. Said valve is provided with a vent opening 24, and is held against the flange 11a of cup 11 by a spring 25, one end of which bears against the valve 20, the other end engaging a nut 26 working on the

threaded portion 14. The tension of the spring 25 is varied by adjusting said nut, and the latter is held in adjusted position by a lock nut 27. The cup 11 is preferably case hardened, and is flared interiorly, as indicated at 28 to effect an air tight joint with the pipe tip 29 of the blow pipe stem 30 carrying the bait 31, and the telescope or air line 32 is connected with the body 10 at the threaded portion 12.

In operation, when the bait is placed in position for lowering it into the molten glass, in the usual manner, the ring 20 is adjusted to the position indicated in dotted lines, Fig. 2, the opening 24 being opposite the vent opening 15, to permit of the usual venting of the system. The valve is locked in this position by reason of the pressure of spring 25 forcing the projection 23 of handle 22 into the depression 18. After making the neck and cam of the glass cylinder, the air pressure must be reduced. This is accomplished by moving the ring or valve 20 to the position shown in full lines, Fig. 2, so that the opening 24 is directly over the opening 16. As the ring is rotated, the spring 25 yields sufficiently to permit the projection 23 to ride over the high portion of the slot 17, and force said projection into the depression 19 to lock the valve in its new position.

It will be understood that the sizes of the openings 15, 16 and 24, may be varied to give the pressure required, and nut 26 may be adjusted, as may be necessary, to insure that the projection 23 will be forced into either depression 18 or 19, when the valve had reached its respective limits of rotation.

Having thus explained the nature of my invention and described an operative manner of constructing and using the same, although without attempting to set forth all of the forms in which it may be made, or all of the forms of its use, what I claim is:—

1. As an improvement in glass drawing machines, a combined coupling and relief valve comprising a cylindrical body shaped to engage one end of a blow pipe stem and provided with spaced apart vent openings of different volumes, and a valve ring rotatably mounted upon said body and having an opening adapted to register with either of said vent openings.

2. As an improvement in glass drawing

2
machines, a combined coupling and relief valve comprising a cylindrical body provided with spaced apart vent openings of different volumes, a valve ring rotatably mounted upon said body and having an opening adapted to register with either of said vent openings, and means for normally preventing rotation of said valve ring when the opening thereof is in register with either 10 of said vent openings.

3. As an improvement in glass drawing machines, a combined coupling and relief valve comprising a cylindrical body provided with an annular flange at one end and 15 also with spaced apart vent openings of different volumes, a valve ring rotatably mounted upon said body and having an opening adapted to register with either of said vent openings, a spring pressing said 20 valve against said flange, and an abutment for the other end of said spring.

4. As an improvement in glass drawing machines, a combined coupling and relief valve comprising a cylindrical body provided with an annular flange at one end and 25 also with spaced apart vent openings of different volumes, a valve ring rotatably mounted upon said body and having an opening adapted to register with either of 30 said vent openings, a spring pressing said valve against said flange, an abutment for the other end of said spring, and means co-operating with said spring for normally preventing rotation of said ring when the opening thereof is in register with either of 35 said vent openings.

5. As an improvement in glass drawing machines, a combined coupling and relief valve comprising a cylindrical body provided with an annular flange at one end and 40 also with spaced apart vent openings of different volumes, a valve ring rotatably mounted upon said body and having an opening adapted to register with either of 45 said vent openings, a spring pressing said valve against said flange, an abutment for the other end of said spring, and a projection carried by said ring, said cylindrical body having a recess provided with locking 50 depressions to receive said projection.

6. As an improvement in glass drawing machines, a combined coupling and relief valve comprising a cylindrical body provided with an annular flange at one end and 55 also with spaced apart vent openings of different volumes, a valve ring rotatably mounted upon said body and having an opening adapted to register with either of 60 said vent openings, a spring pressing said valve against said flange, and an abutment for the other end of said spring, and an operating handle for said ring provided with a projection, said cylindrical body having

a recess provided with locking depressions to receive said projection. 65

7. As an improvement in glass drawing machines, a combined coupling and relief valve comprising a cylindrical body provided with a reduced threaded portion at one end and a flange at the other end, the 70 flanged end being interiorly flared, said body being also provided with spaced apart vent openings, and a valve ring rotatably mounted on said body and having an opening adapted to register with either of 75 said vent openings.

8. As an improvement in glass drawing machines, a combined coupling and relief valve comprising a cylindrical body having an annular flange and spaced apart vent 80 openings, the surface of said body being provided with a recess having depressions corresponding to said vent openings, a valve ring having an opening adapted to register with either of said vent openings, an adjusting nut carried by said body, a spring interposed between said nut and said ring, and an operating handle for said ring provided with a projection extending into said recess. 85

9. As an improvement in glass drawing machines, a combined coupling and relief valve comprising a cylindrical body provided with an annular flange at one end and 90 also with spaced apart vent openings of different volumes, a valve ring rotatably mounted upon said body and having an opening adapted to register with either of 95 said vent openings, a spring pressing said valve against said flange, an abutment for the other end of said spring, said cylindrical 100 body being provided with an exterior recess having depressions, said recess and depressions being covered by said ring, and a projection extending interiorly from said ring into said recess. 105

10. As an improvement in glass drawing machines, a combined coupling and relief valve comprising a cylindrical body, a cup removably connected to said body and provided with an annular flange, said body being provided with an annular flange at one end and also with spaced apart vent openings of different volumes, a valve ring rotatably mounted upon said body and having an opening adapted to register with 115 either of said vent openings, a spring pressing said valve against said flange, and an abutment for the other end of said spring. 110

In testimony whereof I have hereunto set my hand in presence of two subscribing witnesses. 120
